UNITED STATES PATENT OFFICE.

ALFRED W. F. GUEST, OF BROOKLYN, NEW YORK, ASSIGNOR TO MERCENTHALER LINOTYPE COMPANY, A CORPORATION OF NEW YORK.

TYPOGRAPHICAL MACHINE.

1,088,697.

Specification of Letters Patent. Patented Mar. 3, 1914.

Application filed September 11, 1912. Serial No. 719,814.

To all whom it may concern:

Be it known that I, ALFRED W. F. GUEST, a citizen of the United States, and a resident of Brooklyn, county of Kings, and State of New York, have invented a new and useful Improvement in Typographical Machines, of which the following is a specification.

My invention relates to typographical machines, and more particularly to that form thereof wherein are employed a plurality of magazines for the type or matrices, any one of which may be brought into operative relation to the other parts as desired. Such a general arrangement is disclosed in the application for Letters Patent of John R. Rogers, Serial No. 624,426, filed May 1, 1911, wherein is shown a plurality of magazines and means for shifting them into relation to the assembling and distributing mechanisms, and my invention is particularly illustrated in connection therewith. In the use of such machines, it frequently happens that the mouths of the magazines, and particularly of the one or ones beneath that in operation, are left open and exposed to the entrance of foreign matter, as well as of matrices belonging to fonts other than those properly contained therein. For instance, when the channel entrance is shifted, to gain access to the interior parts or to a misplaced matrix, other matrices then in said entrance may "spill" into the magazine mouths, thus entailing inconvenience and delay in the operation of the machine.

It is the purpose of my invention to correct such difficulties, and to that end I provide a cover device to extend over the mouths of the magazines and prevent the accidental entry of matrices, etc. This device preferably takes the form of a pivoted plate, which in the event of a jam, or a matrix protruding from a magazine above it, will yield and thus obviate the breakage or distortion of the parts. In connection with this shiftable cover plate, I also provide means whereby its movement effects the arrest of the distributing mechanism.

In the accompanying drawings, I have shown my invention in preferred form and by way of example, and as applied to the before mentioned Rogers type of machine, but obviously many changes and variations may be made therein, and in its mode of application, and still be comprised within its

spirit. Thus, it may be adapted to other styles of typographical machines, such as those that handle type or dies instead of matrices, or to any kind of machine wherein it is desirable to protect the mouths of the magazine. Generally speaking, I desire it to be distinctly understood that I do not limit myself to any specific form or embodiment, except in so far as such limitations are specified in the claims.

Referring to the drawings: Figure 1 is a transverse vertical section through a portion of a machine having my invention applied thereto; Fig. 2 is a somewhat similar view, showing the parts in different position; Fig. 3 is a perspective view of another portion of the machine, on an enlarged scale, showing the stop mechanism; Fig. 4 is a detail view of the cover plate; and Fig. 5 is a detached perspective view, illustrating the operation of the stop mechanism.

Referring to the drawings, the shift frame A is provided with three magazines A¹, A², A³, any selected one of which may be brought into operative relation to the channel entrance C. The matrices X are moved by the distributor screws B¹ along the distributor rail B, and pass therefrom through the channel entrance into the operative magazine, as for instance the central magazine A², shown in Fig. 1.

The construction and operation of the parts so far described are or may be substantially like those set forth in the said Rogers application and constitute no part of my present invention.

In order to protect and close the mouths of the magazine or magazines, such as A³, below the operative one, against the accidental intrusion of matrices, etc., from above, I provide the cover plate D, located beneath the channel entrance and extending across the ends of the lower magazines. This cover plate is preferably formed at its lower edge with a projecting flange or trough D¹, which is particularly intended to catch matrices falling from the channel entrance C, when the latter is displaced from its normal position. The plate D is shown as pivotally mounted at D² on suitable portions of the stationary frame, and is thus enabled to yield when necessary. The arrangement is such that when the frame A is shifted, the magazines carried thereby are moved freely past the cover plate, which,

however, is always in position to close the mouths of the lower magazine or magazines. In the event that during such shifting, a matrix X should protrude from one of the 5 magazines (as shown in Fig. 2) and contact with the plate, the latter will yield about its pivots, thus obviating any liability to breakage or distortion of the parts. I also take advantage of this movement of the plate, 10 in such circumstances, to arrest the operation of the distributing mechanism, so that the parts may be properly re-adjusted. These connections may be arranged in a 15 variety of ways, and herein I have illustrated them as applied to a well-known form of stop mechanism.

Referring to Figs. 3 and 5, the distributor screws B¹ are rotated by the usual power transmitting devices G, comprising a friction clutch, not shown. Connected to one member of the clutch is the customary cam member H formed with the lateral cam faces H¹. Arranged in proximity to these cam faces is the stop finger J, on the pivotally 25 movable arm J¹, and normally pressed toward its active position by the spring J². This action of the spring is controlled by the arm K carrying the stop piece K¹, which normally rests against the piece L connected 30 to the longitudinally movable stop bar E mounted on the channel entrance C. The plate D is provided with the arm F formed at its end with the bevel or inclined surface F¹, located in proximity to the end of the 35 bar E. When the parts are operating normally, as shown in Fig. 3, the piece L of the bar E engages with the stop piece K¹ on the arm K, and thus holds the finger J in inoperative position. In the event that 40 the cover plate D is swung about its pivot, as for instance by a protruding matrix in the manner previously described, the inclined surface F¹ of the arm F contacts with the end of the bar E and moves it 45 longitudinally, as shown in Fig. 5, to an extent sufficient to disengage the piece L from the stop piece K¹, and thus to permit the spring J² to move the stop finger J into the path of one of the cam faces H¹ of the 50 member H. Due to this engagement of the stop finger and cam face, the continued rotation of the member H effects its lateral movement and opens the friction clutch, and thus arrests the rotation of the screws B¹ 55 and the operation of the distributing mechanism, all in the well-known manner.

As previously stated, I have shown my invention in preferred form and by way of example, but obviously many modifications 60 and variations therein will suggest themselves to those skilled in the art, without departure from its scope.

Having thus described my invention, its construction and mode of operation, what I claim and desire to secure by Letters Pat- 65 ent of the United States is as follows:

1. In a typographical machine, the combination of a movable magazine and a cover to close the upper mouth thereof and thus exclude type or matrices and foreign matter 70 therefrom, the said cover being pivotally mounted on an independent stationary support, so as to be moved from its normal position by type or matrices protruding from the magazine. 75

2. In a typographical machine, the combination of distributing mechanism, a magazine, a movable cover to close the mouth thereof and thus exclude type or matrices and foreign matter therefrom, and connections actuated by the movement of the cover to arrest the distributing mechanism. 80

3. In a typographical machine, the combination of distributing mechanism, a movable magazine, a cover movably mounted on 85 a fixed support to close the mouth thereof and thus exclude type or matrices and foreign matter therefrom, and means actuated by the movement of said cover to arrest the distributing mechanism. 90

4. In a typographical machine, the combination of a plurality of movable superposed magazines and a cover to close the upper mouths of those below the one in operation, the said cover being movably mounted 95 on an independent stationary support, so as to yield in the event of matrices protruding from the magazines. 95

5. In a typographical machine, the combination of the distributing mechanism, and 100 stop devices therefor, with a magazine, and a movable cover to close the upper mouth thereof and thus exclude type or matrices and foreign matter therefrom, the said cover being provided with the arm F to actuate 105 said stop devices.

6. In a typographical machine, the combination of a movable magazine to contain the type or matrices, distributing mechanism, and means for arresting the distributing mechanism if a matrix is protruding 110 from the magazine. 110

7. In a typographical machine, the combination of a movable magazine, distributing mechanism, and devices operated by a 115 matrix protruding from the magazine to arrest the distributing mechanism.

In testimony whereof I hereunto set my hand this fifth day of September, 1912, in the presence of two attesting witnesses.

ALFRED W. F. GUEST.
